UNITED STATES PATENT OFFICE.

JOHN D. IHLDER, OF NEW YORK, N. Y., ASSIGNOR TO OTIS ELEVATOR COMPANY, OF EAST ORANGE, NEW JERSEY, A CORPORATION OF NEW JERSEY.

POTENTIAL SWITCH.

1,025,140.

Specification of Letters Patent.

Patented May 7, 1912.

Application filed February 16, 1905. Serial No. 245,965.

To all whom it may concern:

Be it known that I, JOHN D. IHLDER, a citizen of the United States, residing at New York city, in the county of New York and State of New York, have invented certain new and useful Improvements in Potential Switches, of which the following is a specification.

My invention relates to electric switches, and it has for its object to improve the construction and arrangement of such switches whereby they can be made operative not only upon a fall of potential but also upon any reversal of phase; and my invention consists of the features of construction and arrangement of parts substantially as hereinafter more particularly pointed out.

Referring to the accompanying drawings, Figure 1 is an elevation showing the switch in its normal or closed position; and Fig. 2 is a side view showing how the switch is maintained in such position.

The switch comprises a base S of insulating material, preferably slate, and serves as a support for the various operating parts of the switch.

L, L' are binding posts to which are connected the feeding circuits whose continuity is intended to be controlled. Suitably mounted on the base S with said binding posts L, L' and electrically connected therewith are the contacts O, O'. Adapted to coöperate with said contacts and close the feeding circuits are the switch arms D, D' electrically insulated from each other as shown at R and W but more particularly shown in my Patent No. 594,879, granted to me on December 7, 1897, for an improvement in a potential switch. Said arms are electrically connected to binding posts P, P' from which the feeding circuit may lead to the apparatus with which my switch is used as a protective device.

Suitably pivoted at V on a standard G², which is mounted on the base S at about the center thereof, is a lever N. Integral with said lever or mounted thereon is a U-shaped cross piece to which are rigidly attached the arms D, D' so that any movement given said lever will also be transmitted to said arms.

The lever N comprises a handle F' provided for the purpose of initially closing the feeding circuits through binding posts L, L' and also to manually open said cir-

cuits when desired. Said lever also comprises a catch T extending upwardly therefrom and a switch blade X extending from the lower portion thereof, said switch blade X being adapted to coöperate with the blades Y when the lever is in its lower position. The switch comprising the blades X and Y is provided for the purpose of closing an independent circuit or any circuit derived from the feeding circuits, as desired, or it may act as a buffer only.

Upon the lever N, preferably at the central portion of the cross piece U, is a spring Z constructed and mounted in any suitable manner. In Fig. 2 it is shown as provided with a screw-plug device E for regulating the tension of said spring and a movable piston E'. When the main switch is in its closed position, that is, when the contact portions F and G of the arms D and D' engage, respectively, with the contacts O and O', the said piston E' engages an upwardly projecting lug M which is rigidly mounted on the standard G². The spring Z will thus be compressed so that when the locking means hereinafter described is released said spring will throw the main switch to open position, the weight of the parts thus thrown being sufficient to close the circuit through the switch blades X and Y.

To control the locking device, I use a small direct current or alternating current motor but preferably an alternating current motor of the induction type herein shown as a three-phase motor by reason of the leads A', A'', A'''. The said motor is shown mounted on the lower portion of the base S and on its rotor shaft is carried a cam B. This cam engages an anti-friction roller C' mounted on the lower end of a trigger arm C. This arm C is pivoted at a fixed point V' on a lug G' integral with the standard G² but placed against the base S and is provided with a trigger or catch T' which holds and releases the switch arms D, D' when the cam B is operated in a manner hereinafter described.

The cam B comprises substantially a segment of a disk with a cut away portion at B' so that when the cam is in its upper position, as shown in dotted lines in Fig. 2, the roller C' can ride into said cut away portion to allow the lever arm to be moved toward the left as viewed in Fig. 2 and the catches T, T' released from their locking.

positions. Also mounted on the rotor shaft rigidly with the cam B is a lever H' which extends in an opposite direction from said cam B. The said lever H' may be integral with the cam B, if desired. Suitable abutments or limit stops H and K, herein shown as mounted on the motor, are provided for limiting the movements of the lever H' and hence the cam B.

10 A weight I is detachably mounted near the outer end of the lever H' so that the lever and cam will be held in the position shown in dotted lines in Fig. 2 when the switch is open. The equivalent of a weight, 15 as a spring, suitably mounted on the motor, may of course be used for the purpose of maintaining the lever and cam in their abnormal position, if desired. Or if my invention is used as an anti-reversing switch, as 20 hereinafter explained, no mechanical means is used to move the cam to the dotted line position after the cam has been operated but electrical means is employed for this purpose.

25 The operation of my switch when used as a potential switch is as follows: The motor is connected to a multi-phase circuit so that it tends to rotate in the direction of the arrow a. The rotor will of course move in 30 a fixed direction with the phases of the power circuit in their standard relationship to each other. The lever H' on the rotor shaft prevents rotation of the rotor after it has reached the position where it engages 35 with the limit stop H on the motor frame. While the cam moves in the direction of the arrow a it causes the trigger arm C to rock on its pivot V' and the trigger or catch T' to be placed in position to lock the lever N 40 and consequently the switch arms D, D' in normal position. The cam B thus holds the switch in locked position so long as the current flows properly through the motor A. Should the motor become deenergized by 45 some cause, intentional or otherwise, there would no longer be any torque exerted on the rotor shaft and consequently the weight or spring attached to the outer end of the lever H' would move the cam to the dotted 50 line position as viewed in Fig. 2. When this happens, the lever C is free to be moved until the roller C' assumes the dotted line position. The catch T' is of course at the same time released and the main switch 55 flies open under the pressure of the spring Z.

The operation of my device when used as an anti-reversing switch is very similar to that when employed only as a potential switch. No weight or spring is attached to the lever H' but electrical means are depended upon to move the cam to the dotted line position, that is, said cam will not be returned automatically but by reason of a reversal of the phase relation of the motor circuit. As before, the switch is locked by

the rotation of the cam in the direction indicated by the arrow a. Should now the current to the motor be cut off, the spring Z can not throw the switch as the cam B is heavier than the lever H' and holds the 70 parts in locked position. Or even if B just balances H' the cam and roller are in such relation that the spring Z alone can not operate to move the cam B through the lever C. In other words, after the motor has been 75 energized and the switch locked it will not be unlocked by a deenergization of the motor. In order to open the switch the handle F or cam B must be manually operated. In using the device herein disclosed as an 80 anti-reversing switch the lever H' is unnecessary as the limit stops H and K could obviously be placed so as to be engaged by the cam B. If by some mistake the phases 85 of the power supply should be reversed, that is, if one of the outside lines leading to the motor should be reversed, the induction motor would turn in a direction opposite to that indicated by the arrow, thus causing the cam B to assume the dotted line position. In this position the trigger or catch 90 T' is released allowing the main switch to fly open and interrupt the feeding circuits attached to binding posts L, L'.

It should be noted that when the device 95 described is used as an anti-reversing switch a smaller torque is required to operate the cam B and hold the switch locked as it is not required to act against the weight I or a spring.

Although I have herein shown only two 100 main switch arms and two contacts to operate therewith, it is obvious that it would be within the scope of my invention to use three or more of such switch arms and contacts for any purpose desired.

I have deemed it unnecessary to show any 105 complete circuits for the reason that they may be variously arranged according to the particular use made of the switch. My invention comprises particularly a switch which closes one or more circuits and which are held closed by an alternating current motor and intermediaries. For example, if desired, the circuits leading from the binding posts P, P' may be connected to a double magnetic brake of an electric elevator system and the motor A fed by current from an independent circuit. Or when 110 three switch arms are used they may be placed in series respectively, with the leads of a three phase circuit and a three phase motor tapped to said circuit so that the device may operate as a potential switch. By reference to Patent No. 726,302, granted to 115 me on April 28, 1903, on Electrical Control of Elevators, one adaptation will be clear as the motor may be connected to the three phase circuit therein shown and the switch contacts connected to the brake magnet.

Having thus fully described my invention so that anyone skilled in the art may make, construct and use the same, and without limiting myself to the precise construction 5 of details of the parts disclosed, what I claim and desire to secure by Letters Patent is:

1. The combination of a switch, of an electric motor, a cam operated by the motor, 10 and means positively actuated by the said cam for holding the said switch in closed position.

2. The combination of a switch, an alternating current motor, a cam operated by the 15 motor, and means operated by the said cam into position to positively hold the said switch in closed position.

3. The combination with an electrical switch, a rotary motor, a cam on the shaft 20 of said motor, and means operated by said cam to lock said switch in closed position so long as the potential applied to said motor does not fall below a pre-determined value.

25 4. The combination with a switch, of an alternating current motor, a cam on the motor shaft, and means operated by said cam into position to hold said switch closed and for maintaining said switch in closed position 30 so long as the potential applied to the motor does not fall below a pre-determined value.

5. The combination with a switch, of an alternating current motor, means for locking 35 said switch in closed position, and a cam on the motor shaft for positively actuating said locking means when said motor is sufficiently energized.

6. The combination with a switch, an alternating current motor, means for locking 40 said switch in closed position, a cam on the motor shaft for positively actuating the locking means when said motor is energized, and means for releasing said locking means 45 when said motor is deenergized.

7. The combination with a switch, of an alternating current motor, locking means, and a cam operated by said motor when energized to actuate said locking means to 50 maintain said switch in closed position, and means for releasing said locking means and opening said switch when said motor is deenergized.

8. The combination with a switch, of an 55 alternating current motor, means comprising a pivoted lever and a trigger for locking said switch in closed position, a catch connected to the switch and constructed to co-operate with said trigger, a cam operated 60 by the motor when energized positively to actuate said lever and maintain said switch in closed position, and means for releasing said locking means and opening said switch when said motor is deenergized.

65 9. The combination with a switch, of an

alternating current motor, means comprising a pivoted lever and a catch carried thereby for locking said switch in closed position, a catch mounted on a switch and constructed to engage with the first-named 75 catch, a cam on the motor shaft and operated thereby when said motor is energized positively to actuate said lever, to lock said switch in closed position, a lever rigidly connected with said cam, limit stops for said lever, and means connected with said lever to move the cam upon the deenergization of said motor to such a position that the locking device will be released and the switch opened.

10. The combination with a switch comprising a switch arm, of a rotary motor, a cam carried thereby, a lever having an arm extending into position to be operated by the cam, and interlocking members carried by and rigid with the switch arm and said lever, respectively.

11. The combination with a base, of a stationary switch contact carried thereby, the switch arm having a contact movable 90 into engagement with the stationary contact, a rotary motor carried by the base, a cam secured to the rotary member of the motor, a lever pivoted to the base, interlocking members connected to said lever and 95 switch arm respectively, said lever being operable by the cam into position to so dispose said members as to hold the switch closed when the motor is energized, and means to move said cam in opposition to 100 the power of the motor to disengage said interlocking members.

12. The combination with an electric switch, of a rotary multiphase alternating current electric motor, a cam connected to 105 the shaft of said motor, and means positively operated and moved by said cam into position to lock said switch in closed position.

13. The combination with a manual 110 switch, of a multiphase alternating current electric motor, a cam connected to the motor shaft, and means positively operated upon by said cam and moved thereby into position to hold said switch in closed position.

14. The combination with a switch, of an alternating current motor, a pivoted lever and a trigger connected thereto, a catch connected to the switch and co-acting with 115 said trigger to form a locking device, and a cam operated by the motor when energized to positively actuate said lever and hold the trigger in engagement with said catch and thereby maintain the switch in closed position.

15. The combination with a switch, of an alternating current motor, means comprising a pivoted lever and a catch for locking said switch in closed position, a catch mounted on the switch and constructed to 120

engage the first-named catch, a cam on the motor shaft and operated thereby when said motor is energized to positively actuate said lever to lock said switch in closed position, 5 a lever rigidly connected with said cam, and limit stops for said lever.

16. The combination with an electric switch, of an electric rotary motor, a pivoted lever, a trigger connected to said lever, a 10 catch connected to a movable part of said switch, and a cam operated by said motor to positively actuate said lever and hold said trigger in engagement with the catch while the switch is in closed position and 15 the motor is energized.

17. The combination with an electric switch, of an alternating current induction motor, a pivoted lever, a trigger connected to said lever and movable therewith, a catch 20 carried by a movable part of said switch co-acting with said trigger to hold the switch in closed position when the lever is actuated, a cam carried by the shaft of said induction motor and positively actuating said lever 25 upon the energization of said motor by alternating current having a predetermined phase relation, a lever connected to the motor shaft, limit stops for said lever, and a device for returning the lever, shaft and 30 cam to normal position when the current is cut off from the motor.

18. The combination with an electric switch, of an alternating current induction motor, a cam operated by said motor, means for limiting the movements of said cam, 35 and a device positively actuated by said cam to lock the switch in closed position when the motor receives current having a predetermined phase relation.

19. The combination with a switch comprising a plurality of contacts and switch arms, of a lever on which said switch arms are mounted, a catch mounted on said lever, resilient means for throwing open said switch, a fixed lug for engaging said resilient means, a locking device including a trigger 40 for engaging said catch, an alternating current motor, a cam connected thereto, and so constructed and arranged that when said cam is moved in one direction it shall actuate said locking device to hold the said switch closed, and when moved in another direction it shall allow said locking device 45 to be released and the switch thrown open by said resilient means.

In witness whereof, I have hereunto signed my name in the presence of two subscribing witnesses.

JOHN D. IHLDER.
